UNITED STATES PATENT OFFICE.

WILLIAM PELHAM BULLIVANT, OF LONDON, ENGLAND.

RAILWAY-BRAKE.

SPECIFICATION forming part of Letters Patent No. 656,090, dated August 14, 1900.

Application filed March 13, 1900. Serial No. 8,502. (No model.)

To all whom it may concern:

Be it known that I, WILLIAM PELHAM BULLIVANT, a subject of the Queen of Great Britain and Ireland, and a resident of 72 Mark 5 Lane, in the city of London, England, have invented certain new and useful Improvements in or Relating to Railway-Brakes, (for which I have applied for a patent in Great Britain, No. 16,497, dated August 14, 1899,) 10 which invention is fully set forth in the following specification.

My invention relates to railway-brake apparatus of the class in which jaws carried on a locomotive, brake-van, or other vehicle are 15 operated to grip either one or both of the rails or a rope or ropes or other stationary device or devices. My said invention is particularly applicable for use on railways having a steep gradient; and it has for its objects to provide 20 means whereby the gripping and the necessary lowering and raising of the jaws into and out of their operative position can be effected at the requisite times by steam or other motive agent and means whereby the said apparatus is prevented from operating at the 25 junctions and other parts where the rail or rails or its or their equivalent cannot be gripped. I will by reference to the accompanying drawings describe an arrangement 30 according to my invention as being operated by steam and arranged on a locomotive for gripping both of the rails; but it is to be understood that the invention is not limited thereto.

35 In the drawings, Figure 1 is a view of the apparatus shown half in elevation and half in vertical section. Fig. 2 is a vertical section taken at right angles to Fig. 1; and Fig. 3 is an elevation showing the apparatus as 40 applied to the vehicle, only part of which latter is represented. Fig. 4 is a diagrammatic plan view. Fig. 5 is a sectional view of the slide-valve.

I provide for each rail a pair of jaw-levers 45 or jaws A, pivoted in a vertically-movable slide B by means of a pivot a, working in a horizontal slot a', Figs. 1 and 2, in the slide, in order to enable the jaws to adjust themselves in a horizontal direction. The jaws 50 have connected to their upper ends the lower and outer ends of two toggle-links C, whose upper ends are pivoted by a pin D, guided

in the slide B, to the rod E of a piston F, raised and lowered in a cylinder F' by steam-pressure. The said slide B is free to move 55 in a rigid frame G, fixed to the locomotive, and is provided with buffers B' for absorbing shock and for supporting the slide in its lowest position. To the frame G is pivoted a segmental dog or cam H, connected by a slot I 60 and pin J to the piston-rod E in such manner that the said dog or cam will always be moved angularly when the piston-rod is raised and lowered. The dog or cam H engages with the upper part of the slide B to insure that 65 the jaws A and slide shall move as one piece during the time that the said jaws are being lowered into their operative position—that is to say, during the first part of the downward stroke. When the jaws A reach this position, 70 the further descent of the slide B is arrested by the aforesaid buffers B', and the dog or cam H having also reached a portion b of the slide B curved concentrically with the pivot h of the said dog or cam the piston-rod E descends independently of the slide B, and thereby causes the jaws A to be closed upon the rail K.

During the releasing operation of the brake the dog or cam H first prevents the slide B 80 from ascending, and thereby insures the jaws A opening to disengage from the rail K, and then releases the slide, so that it and the jaws ascend together away from the rail.

The chamber containing the valve L for controlling the supply and exhaust of steam to and from the cylinder F' is connected to the upper and lower ends of the cylinder F' by pipes and passages l l', respectively, Figs. 3 and 4, and with the steam-generator by a 90 pipe l², l³ being the exhaust from the valve-chamber. The valve-rod l⁴, Fig. 5, is connected to a weighted lever M, having a downwardly-extending arm m, carrying a roller m', adapted to engage with obstructions, such as 95 m², (partly shown by dotted lines in Fig. 3,) placed at those parts of the track at which it would be dangerous or undesirable that the brakes should be applied. To this weighted lever M is attached by a pin-and-slot connection m³ the brake-controlling gear, consisting, preferably, of a vertically-adjustable nut N and a screwed shaft n, and lever-handle n', under the control of the brakeman.

In the normal working of the apparatus the weighted lever M and the valve L are maintained in the raised position by the brake-controlling gear, the lower end of each of the 5 steam-cylinders F' being fully open to the steam-supply, and the before-mentioned jaws A are thereby supported in their raised or inoperative positions. When the brakes are to be applied, the brake-controlling gear is operated so as to release the weighted levers M, which then immediately descend into the position shown in dotted lines in Fig. 3 and through the valve L cause the steam to be exhausted from below the pistons F and 10 steam from the boiler to be admitted above the pistons, so as to force down the piston-rods E, and thereby cause the jaws A to grip the rails K, as hereinbefore described. Should this operation, however, fail to stop the locomotive before the locomotive reaches a junction or the like, the before-mentioned obstruction m^2 in the track raises the weighted levers M, and thus temporarily causes the 15 brake-jaws A to ascend into their inoperative positions, the brakes being afterward automatically reapplied by the descent of the weighted levers M when the roller m' leaves the obstruction. The pivots a of the jaws A are free to adjust themselves in a horizontal 20 direction in an opening a' in the slides B, so as to compensate for sidewise displacement of the locomotive on the rails K, due to curves, for example. To enable the brakes to be maintained in operative positions when 25 the locomotive is not under steam, stops O are inserted beneath the buffers B' in the position indicated by dot-and-dash lines at the right-hand side of Fig. 1 for supporting the pistons F in the raised position.

Having now particularly described and ascertained the nature of this invention and in what manner the same is to be performed, I declare that what I claim is—

1. In a railway brake apparatus, the combination with a stationary frame and motor mechanism thereon, of a slide vertically mov-

able in the stationary frame, two jaws pivoted in the slide and adapted at their lower ends to grip a stationary rail or device extending along a railway-track, toggle-links connecting the upper ends of the jaws to each other and to the motor mechanism and means whereby the slide is caused positively to descend to its lower position before the jaws are closed and to rise again only after the 55 jaws are reopened, substantially as described.

2. In railway brake apparatus the combination with a stationary frame and motor mechanism thereon of a slide vertically movable in the stationary frame, two jaws pivoted in the slide and adapted at their lower ends to grip a stationary rail or device extending along a railway-track, toggle-links connecting the upper ends of the jaws to each other and to the motor mechanism, abutments on the slide and stationary frame for arresting the descent of the slide, a dog or cam pivoted to the fixed frame and operatively connected to the motor mechanism, and an abutment on the slide for engaging 60 with the dog or cam, substantially as set forth.

3. In railway brake apparatus, the combination with a stationary frame and motor mechanism thereon, of a slide vertically movable in the stationary frame, two jaws pivoted 75 in the slide and adapted at their lower ends to grip a stationary rail or device extending along a railway-track, a slotted connection between the pivot of the jaws and the slide for enabling the jaws to adjust themselves in a horizontal direction, and toggle-links connecting the upper ends of the jaws to each other and to the motor mechanism, for opening and closing the said jaws, substantially as set forth.

In testimony whereof I have signed this 80 specification in the presence of two subscribing witnesses.

WILLIAM PELHAM BULLIVANT.
